UNITED STATES PATENT OFFICE.

WILLIAM M. MACKAY, OF EAST ORANGE, NEW JERSEY.

SECTIONAL STEAM OR WATER BOILER WITH WATER-GRAVE.

1,310,198.

Specification of Letters Patent. Patented July 15, 1919.

Application filed July 23, 1917. Serial No. 182,102.

To all whom it may concern:

Be it known that I, WILLIAM M. MACKAY, a citizen of the United States, residing at 73 Warrington Place, East Orange, county of 5 Essex, and State of New Jersey, have invented certain new and useful Improvements in Sectional Steam or Water Boilers with Water-Grates, fully described and represented in the following specification and 10 accompanying drawings, forming a part of the same.

The present invention relates to a steam or water-boiler formed of substantially flat vertical sections any number of which may 15 be assembled to form a boiler, such sections having seats upon their margins to contact with one another when thus assembled, and spaces between such seats forming flues which extend between the several sections to 20 a common smoke-outlet. Each section has a single flue-space only, extended along each side.

The firebox sections comprise each a water-plate of L-shape, the horizontal arms forming the top of the firebox and the vertical arms its rear side, the front being closed by a water-plate extended the entire width of the sections when assembled. The grate is extended from the water-front to the vertical arms about midway of its height, and the only smoke-outlet from the firebox is below the grate between the lower ends of the said arms. The invention consists in the particular constructive features which produce a 35 downward draft through the grate, and which form flue-spaces between all parts of the adjoining sections and provides an escape-flue for the smoke through the front ends of the upper sections at the sides of the boiler.

40 The invention will be understood by reference to the annexed drawing, in which Figure 1 is a front elevation of a boiler for operation in connection with a lower-grate and ash-pit; Fig. 2 is a side elevation of the same; Fig. 3 is a section of portion of the water-front on line 3-3 in Fig. 10; Fig. 4 is an end view, and Fig. 5 a side view of one of the circulating pipes for the water-grate bars.

50 Fig. 6 is a longitudinal section of the boiler with the extreme top of the base, the view being taken through one of the water-grates and between two of the firebox sections; Fig. 7 is a front elevation of three sections at the left-hand side of the boiler; Fig. 8 is a section on line 8-8 in

Fig. 10; Fig. 9 is a horizontal section on line 9-9 in Fig. 6; Fig. 10 shows the inner side of the water-front with one of the water-grates in section; Fig. 11 is a perspective view of the ledge upon the fire-box sections with the grate-bar guard thereon; Fig. 12 shows the shank of one of the water-grate bars; Fig. 13 is a side view of the same; Fig. 14 a side view of the front corner of 65 one of the horizontal arms with transverse water connection; and Fig. 15 is a section on line 15-15 in Fig. 14.

The boiler is represented with four firebox sections marked A in Fig. 9 and two 70 end sections marked B.

The fire-box sections shown in Figs. 6 and 7 are formed of a flat water-plate having horizontal arm a' and vertical arm a^2 . The sections are assembled upon a base A^3 , 75 with a water-front B^4 which fits beneath the front ends of the fire-box sections to support them.

Enlarged water-channels d are formed along the outer margins of the arms, with 80 sloping walls which produce narrow joint seats d' . Similar enlarged channels d form joint seats d^2 along the inner margins of the arms, and extend only part way down the inner margin of the vertical arm, so as 85 to leave a flue-opening or inlet e' upon the inner side of each vertical arm near its lower end.

The water-space in the arms a and a^2 is continuous within the channels d so as to 90 permit a free circulation of the water within both arms, and from the vertical arms to the horizontal arms. The tops of all the sections are connected separately with the header C, and the lower ends separately with 95 the header D, through which water is supplied indirectly to the sections.

The said hollow channels and joint-seats form, when the sections are adjoining and thus connected, as shown in Figs. 6 and 7, 100 flue-passages e extending between all parts of both arms and opening at e' upon the inner side of the vertical arms at the lower end of the same.

This construction of the arms enables each 110 to form a single independent direct water passage from the water-inlet D to the steam or water-outlet C; while the joint-seats upon the edges of the arm form at opposite sides of the same a single flue-passage e which 115 leads from the flue-opening e' to the transverse passage e later described.

The outer side of the vertical arm is of convex contour or profile, so that the seats at the outer edge of the arm incline toward the inner edge of the arm at its lower end, 5 where it is formed with a flat surface or foot e^2 to rest upon the base. When the sections are assembled, these seats d' and d^2 contact with one another, as shown in Figs. 7 and 9. The water-channels project from 10 the surfaces of the plates sufficiently to form smooth passages e between the sections.

A transverse flue-opening c is extended through the plate of the horizontal arm near its front end, such openings coinciding in 15 the several fire-box sections.

The ends of the horizontal arms are covered, as shown in Figs. 1, 2 and 6, by a front-plate m' having doors n' for cleaning out the spaces e . Each end-section, as shown in 20 Fig. 7, is formed with an opening c' coincident with the transverse passages c . One of its openings may be provided with a smoke-nozzle q' , and the other with a draft-door c^2 , as shown in Fig. 1.

25 The smoke-passages between the sections have a narrow throat at the smoke inlet e' and widened gradually toward the transverse opening c , such narrow throat causing the flow of the gases into each of the flues 30 and compelling the smoke and gases to pass through them all on their way to the chimney, thus heating all parts of the boiler equally; while affording space in the wider portion of the flue to complete the combustion. 35

The end sections a^2 have the same external contour as the fire-box sections, and are also formed each with a flat plate a^3 to close the ends of the fire-box. The end sections a^3 40 have, upon the inner side, enlarged water-channels and seats corresponding with those upon the fire-box sections, and have each a transverse opening c' coinciding with the openings c . (See Figs. 7 and 9.)

45 The front B^4 is shown as a hollow water-plate with upper door B' and lower door B^2 , and hollow grate-bars f are shown screwed into the water-plate between the upper and lower doors, and extended to the vertical arms b which are provided just above the flue-opening e' with a ledge g to support the ends of the bars.

The grate formed of the hollow bars f divides the fire-box into upper and lower fire-chambers, the upper chamber having no outlet to the chimney, so that the draft is compelled to move downward through such grate to reach the smoke-inlets e' .

The end of each hollow grate-bar is provided with a pin g' to rest upon the ledge g , and space between the end of the grate-bar and the arm b is provided to permit an end movement of the bar whenever it is necessary to replace such a bar by unscrewing it from the water-front B .

Fig. 11 shows a guard m having notches upon its under side adapted to embrace the pins g' as they rest upon the ledge g , and thus hold the grate-bars in alinement.

An inclined partition h is extended from 70 side to side of the water-front between the doors, reaching across the front ends of all the grate-bars.

Return or circulating-tubes i open at both 75 ends are screwed into such partition, one of them projecting into each of the grate-bars and extending nearly to its inner end. The partition thus divides the interior of the front into two water-spaces, which form common communications respectively with 80 the grate-bars and the tubes i .

A removable plug f' is fitted in the front before each of the tubes i to permit of the introduction of the tubes, and the tubes, as 85 shown in Figs. 3 and 4, are made with key-like ribs f^2 within their threaded ends to engage a suitable wrench for screwing them into and out of the partition when the block is removed.

Supply-pipes j connect the lower water 90 space of the water-front with the lower part of the end section, and pipes k connect the upper water-space with the upper part of the end section, and the inclined partition h in such front compels all the water which 95 enters the lower space to pass through the tubes i and the hollow grates f to reach the upper space from which it passes to the end sections.

The connection of all the sections by a 100 header C at the top and a header D at the bottom affords a separate circulation of water through each of the sections if used for a water heating boiler, and the restricted 105 smoke-inlets e' cause a movement of the products of combustion uniformly through all of the flues e , and each section is thus enabled to contribute equally to the work of the boiler.

Where the base is formed with an ash-pit 110 A^3 and ash-door A^2 , as shown in Figs. 1, 2 and 6, a supplemental grate l may be fitted to the top of the base, thus providing for the consumption of fuel in the lower fire-chamber.

As such lower chamber is in connection 115 with the smoke-inlets e' , a fire may be readily started upon the lower grate by supplying fuel through the door B^2 , and may be maintained thereon to arrest any fuel that falls from the upper grate, and complete its combustion.

The fire on the lower grate aids very much in effecting the combustion of the coal upon the upper grate, as the smoke and gases 125 which descend through the upper grate are maintained at a high temperature in the lower chamber of the fire-box and their combustion is promoted before they enter the flues between the sections.

Such double combustion upon the two grates consumes the heavy smoke which is emitted from the chimneys of soft coal furnaces, with boilers of ordinary combustion 5 having a single grate only.

The bars of the lower grate *l* would be set close together to prevent any loss of fuel, while the grate formed of the water-bars *f* are set farther apart, as shown in 10 Fig. 10, (which represents the inner side of the water-front) to permit the combustion of soft coal with a downward draft.

To permit the slicing of the soft coal upon such a grate, stoke-holes *n* are forced 15 through the water-front, as shown in Fig. 8, for access to the spaces between all of the bars.

Having thus set forth the nature of the invention what is claimed herein is:

20 1. A vertical firebox section for a steam or water-boiler, comprising a water-plate of L-shape having a horizontal arm with substantially horizontal edges, and a vertical arm with its lower edges gradually sloped 25 toward one another to its bottom end, the arms having enlarged hollow channels along the margin with opposite sloping walls forming joint-seats which extend along the outer margins of both arms and along the inner margin of the horizontal arm, the said enlarged hollow channels and 30 joint-seats forming, when the sections are assembled, a flue extending between all parts 35 of the arms and forming a smoke-outlet upon the inner side of the vertical arms at the lower end of the same.

2. A vertical firebox section for a steam or water-boiler, comprising a water-plate of 40 L-shape having a horizontal arm and a vertical arm and joint-seats upon opposite sides along the outer edges of both arms, and joint-seats upon opposite sides along the inner edge of the horizontal arm and 45 part way down the inner side of the vertical arm, the seats forming, when the sections are assembled, flue-spaces extending between all parts of both arms, and the horizontal arm having a transverse flue-opening 50 through the water-plate to permit the lateral passage of the smoke from said flue.

3. A vertical firebox section for a steam or water-boiler comprising a water-plate of L-shape having a horizontal arm with substantially horizontal edges, and a vertical arm with its lower edges sloped in relation to one another to the bottom end of said arm, the arms having enlarged hollow channels along 55 the outer margins of both arms and along the inner margin of the horizontal arm and part way down the inner margin of the vertical arm, the channels having opposite sloping walls forming joint-seats upon opposite sides of the sections, the said joint-seats 60 forming, when the sections are assembled, a

flue extending between all parts of the arms and forming a smoke-inlet upon the inner side of the vertical arm at the lower end of the same, and the sections having a transverse ledge upon the inner side of the vertical arm at the top of the smoke-inlet to support a grate above the smoke-inlet and thus divide the space within the section into two combustion-chambers, the upper of which 70 operates only with a downward draft. 75

4. A vertical firebox section for a steam or water-boiler, comprising a water-plate of L-shape having a horizontal arm with substantially horizontal edges and a vertical arm with edges gradually sloped toward one another, the arms having enlarged hollow channels along the margin with opposite sloping walls forming joint-seats which extend along the outer margins of both arms and along the inner margin of the horizontal arm; the said water-channels and joint-seats forming flues when the sections are joined together and a smoke-inlet upon the inner side of the vertical arm near its foot, and the horizontal arm having a transverse flue-opening between the water-channels near its forward end, the sloping of the water-channels in the vertical arm in relation to one another forming a gradually expanding smoke-flue between the channels in the vertical arm, to retard the movement of the escaping gases toward the transverse flue-opening. 80 85 90 95

5. A steam or water-boiler having a plurality of firebox sections, comprising each a water-plate of L-shape having a horizontal arm and a vertical arm with joint-seats upon the opposite sides along the outer edges of both arms, and joint-seats upon the opposite sides along the inner edges of the horizontal arms and part way down the inner sides of the vertical arms, such seats forming a flue-space extending between all parts of adjoining sections and a smoke outlet upon the inner side of the vertical arm 100 at the lower end of the same, end-sections of the same outline as the L-shaped section for closing the ends of the firebox, a base receiving the lower ends of the vertical arms, a water-front fitted between the horizontal arms and the base, and a grate fitted 105 between the sections between their vertical arms and the water-front, and dividing the space within the sections into two combustion-chambers, the chamber below the grate 110 having the only communication with the smoke-outlet and the upper chamber operating with downward draft only. 115 120

6. A steam or water-boiler having a plurality of firebox sections with marginal 125 joint-seats forming flue-spaces between all parts of the adjoining sections, a smoke-outlet upon the inner side of the vertical arms at the lower end of the same, a ledge on each vertical arm over the smoke-outlet, 130

- end-sections of the same outline as the L-shaped sections, a base receiving the lower end of the vertical arms, a water-front fitted between the horizontal arms and the base,
5 an oblique partition within the water-front dividing the water-space into upper and lower water-chambers, hollow grate-bars projected from the upper water-chamber to the ledges over the smoke-outlet, circulat-
10 ing-tubes secured in the oblique partition in communication with the lower water-chamber and extending into the said grate-bars and circulating pipes connecting the end-sections with the upper and lower water-
15 chambers in the water-front, as and for the purpose set forth.
7. A steam or hot water boiler having end-sections as described and a plurality of intermediate L-shaped firebox-sections with
20 horizontal arms at the top of the firebox and vertical arms at its rear end, a base supporting the ends of the vertical arms, a water-front closing the front of the firebox, an oblique partition extended across the
25 water-front dividing the front into upper and lower water-chambers, hollow grate-bars projected from the upper water-chamber across the firebox to the vertical arms, return-tubes secured in the partition in
30 communication with the lower water-chamber and extending one into each of the grate-

bars, and the chambers above and below the oblique partition forming common communications respectively with the grate-bars and with the return-tubes, a water supply pipe extended into the lower water-chamber, and a water-outlet pipe extended from the upper chamber, the construction causing all the water entering the water-front to circulate through the grate-bars.

8. A steam or hot water boiler having a plurality of L-shaped firebox-sections with marginal joint-seats forming flue-spaces between all parts of the adjoining sections with a smoke-outlet near the bottom of each section and a ledge at the top of such outlet, a base supporting the firebox-sections, end-sections and a water-front closing the firebox, an oblique partition extending wholly across the upper water-front and dividing the water-front into upper and lower water-chambers, a series of threaded holes extended into the upper water-chamber, water grate-bars screwed each into one of the threaded holes and extended to the ledges upon the vertical arms, and return-tubes screwed into the oblique partition and extending into the grate-bars, as and for the purpose set forth.

In testimony whereof I have hereunto set my hand.

WILLIAM M. MACKAY.
